J. HILL.
Feed-Indicator for Cotton-Openers.

No. 224,185.

Patented Feb. 3, 1880.

UNITED STATES PATENT OFFICE.

JOHN HILL, OF COLUMBUS, GEORGIA.

FEED-INDICATOR FOR COTTON-OPENERS.

SPECIFICATION forming part of Letters Patent No. 224,185, dated February 3, 1880.

Application filed November 21, 1879.

To all whom it may concern:

Be it known that I, JOHN HILL, of Columbus, in the county of Muscogee and State of Georgia, have invented a new and Improved 5 Feed-Indicator for Cotton-Openers; and I do hereby declare that the following is a full, clear, and exact description of the same, reference being had to the accompanying drawings, forming part of this specification, in 10 which—

Figure 1 is an inside view of a building with the two openers in position upon different floors and connected by the hollow trunk. Fig. 2 is a vertical section through the line x x , looking in the direction of the arrow. Fig. 3 is a 15 detail of the scale index-hand and connecting-rod.

My invention relates to a convenient and certain means for determining the quantity of 20 cotton to be fed to cotton-openers. The latter machines are devices which serve to tear up and loosen the tufts of cotton as they come from the bale and distribute the fiber in the form of a fleece. In using these openers two 25 are sometimes employed together to act successively upon the cotton; or one opener may be employed in connection with a lapping-machine, the function of which latter is to press together and compact into a fleece. In 30 either case a hollow trunk has been employed as a conduit, in connection with a blast of air passing through the same, to act as a vehicle to carry the fleece from one opener to the other, or from the opener to the lapping-machine, 35 which second machine is generally located upon a different floor, or at a point more or less remote from the first.

My invention has more special reference to what is known as "Kitson's Trunk System of 40 Opening Cotton;" but it can be used in any similar system where the opener is located at some distance from the second opener or lapper and cotton is supplied from the first to the second through a trunk or flue.

The invention consists in making the boxes 45 of the upper feed-roll of the second opener or lapper vertically adjustable and connecting them with an index-hand within sight of the operator at the first machine, so that said operator, at a point remote from the second machine, can tell the amount of cotton fed to the

second machine by the rise or fall of the movable roller due to the passage of a greater or less quantity of cotton to the second machine.

In the drawings, A and B represent two 55 floors of the building, upon which are located, respectively, the first and second openers, C and D, of which, as here shown, the first opener, C, is located on the first floor, and the second opener, D, on the floor above, and which second opener, D, may be supplanted by a lapping-machine, as described. These two machines are connected by a hollow trunk or flue, E, which leads from the discharge end of the first machine to the feed end of the remote machine, 60 and through which a blast of air is forced to carry the fleece along.

Cotton is supplied to the first machine, and after its fibers are loosened it passes, in connection with the propelling drafts of air and 70 collecting-condensers, directly to the feed attachment of the second machine, the amount of cotton supplied to the second machine being determined by that passing through the first.

For evenness of results it becomes important 75 that some ready means of determining the amount of cotton being used by the second machine should be afforded to the operator feeding the supply to the first. To accomplish 80 this I place on each journal of the upper feed-roll, F, of the second machine a vertically-movable box or half-box, a , which rises and falls according to the thickness of the feed 85 passing between the rolls. From each of these boxes I suspend links b , loosely attached at their lower ends to the opposite ends of a horizontal bar, c , which latter, near its middle, is connected to the horizontal lever d , having a fixed fulcrum at one end and a weight, e , at 90 the other, the point of connection between the bar c and lever d being close to the fulcrum of the latter, so that the range of movement will be multiplied to increase the sensitiveness of the indicator.

The weight e may be supplanted by a spring, and its gravity or tension is sufficient to take up all lost motion in the connections and to cause the boxes to closely follow the movements of the journals.

To the weighted end of the lever d a connecting-rod, f , is attached, whose position is de-

terminated by the relative situations of the two machines and the connecting-trunk. As shown, it passes downward to the floor beneath, where the first machine is located, and connects with the crank *g* of a rock-shaft, *h*, arranged in bearings on the trunk, which latter has a second crank, *i*, from which is suspended a rod, *j*, carrying an index-hand, *k*, adapted to move over a scale, in front of the operator, which scale is determined by the extreme limit of movement between the feed-rolls of the second machine.

With this arrangement it will be seen, without further description, that the operator below has constantly before him an indicator to show the amount of cotton passing into the second machine.

With the arrangement of the bar *c* and lever *d* it is not necessary that there should be a regular and even thickness of sheet under the bite of the feed-roll of the second machine, as the suspended bar *c* is differential as attached to the lever *d* below—*i. e.*, the movement of the lever *d* is commensurate with the quantity of cotton fed, and not simply the thickness of the fleece passing between; for if a large bulk of fleece passes at one end of the roll and nothing at the other, the horizontal bar *c* acts as a lever to rise only at one end, and as its connection with the subjacent lever is at a middle point it only pulls said lever half the distance up that it would if both ends raised the distance of the maximum thickness of the fleece.

The weight or spring attached to the long arm of the second lever I use not only to take up lost motion, but as a power to hold into position the top roll for proper strength of bite.

As a modification of my invention I may employ a different train of mechanism for transmitting the motion from one machine to the other—as, for instance, a cord or wire may, in

many cases, be used to advantage in the place of the connecting-rod, rock-shaft, and cranks.

In defining the scope of my invention more clearly, I would state that I do not limit myself to combining the index-hand of the first machine with the movable roll of the second, but may combine it with any two parts of the second machine through which the sheet or fleece of cotton is fed when one of said parts is made adjustable to suit the thickness of the fleece being fed, and by such automatic adjustment operates the indicator of the first machine.

I disclaim fully such indicators when combined simply with the feed devices of the same machine.

Having thus described my invention, what I claim as new is—

1. The combination, with the two machines C and D, situated at a distance from each other, and connected by a trunk, as described, of bearings mounted upon the second machine, through which the fleece is fed to said machine, one of said bearings being movable, as described, and adapted to accommodate itself automatically to the varying thickness of the fleece, and an indicator-hand situated upon the first machine and connected with the said movable bearing of the second machine, substantially as described.

2. The combination of the two machines C D, the connecting-trunk, the feed-rolls mounted on the second machine, and one of which is made movable, the links *b*, horizontal suspended bar *c*, the lever *d*, and the indicator, and mechanism, substantially as described, connecting said lever with the said indicator on the first machine, as set forth.

JOHN HILL.
